SHOWER ENCLOSURE

Stanley F. Korol, Mansfield, Ohio, assignor to Borg-Warner Corporation, Chicago, Ill.

Filed Feb. 28, 1972, Ser. No. 230,172

Term of patent 14 years

Int. Cl. D23—02

U.S. Cl. D23—69

FIG. 1 is a perspective view of a shower enclosure embodying my new design; and

FIG. 2 is a cross sectional view taken on line 2—2 of FIG. 1.

The broken line representation of a bathtub in FIG. 1 is for purpose of illustration only. It is to be understood that the pattern is complete in the panels where indicated.

I claim:

The ornamental design for a shower enclosure, as shown and described.
